[57] CLAIM

The ornamental design for a disinfectant tray or similar article, substantially as shown and described.

DESCRIPTION

FIG. 1 is a perspective view of the disinfectant tray or similar article showing our new design, with the handle in the closed position;

FIG. 2 is a perspective view thereof showing the handle in an open position;

FIG. 3 is a top plan view of the tray of FIG. 1;

FIG. 4 is a bottom plan view of the tray of FIG. 1;

FIG. 5 is a front elevational view of the tray of FIG. 1;

and

FIG. 7 is a left side elevational view of the tray of FIG. 1 with the opposite side being a mirror image.

The apertures of FIGS. 2 and 4 are incompletely shown for ease of illustration but form a repeating pattern such as shown in FIG. 3.
